United States Patent Office

Des. 222,384
Patented Oct. 19, 1971

222,384

TAPE MEASURE

Michael A. Cousins, Huntington, N.Y., assignor to
Justus Roe & Sons, Inc., Patchogue, N.Y.

Filed May 12, 1970, Ser. No. 22,939

Term of patent 14 years

Int. Cl. D10—04

U.S. Cl. D52—1

FIG. 1 is a top plan view of a tape measure showing my new design;

FIG. 2 is a side elevation thereof;

FIG. 3 is a bottom plan view; and

FIG. 4 is a perspective view thereof.

I claim:

The ornamental design for a tape measure, as shown.
